SHOELACE KNOT RETAINER

Albert S. Hakim, Monroe, La.

Filed Feb. 25, 1964, Ser. No. 78,774

Term of patent 14 years

(Cl. D7—6)

FIG. 1.

FIG. 2.

FIG. 4.

FIG. 3.

FIGURE 1 is an exploded perspective view of a shoelace knot retainer showing my new design;

FIGURE 2 is a side elevational view thereof as it appears when assembled;

FIGURE 3 is a detail cross-sectional view taken on the vertical plane of line 3—3 of FIGURE 2, looking in the direction of the arrows; and

FIGURE 4 is a top plan view of FIGURE 2.

The characteristic features of my design reside in the provision on the cap for a shoelace fastener of the type disclosed wherein the sidewall thereof is milled; the circumferential marginal edge of the end wall has an inverted frusto-conical configuration terminating in a planar surface; and a bell superimposed on the planar surface, substantially as shown.

I claim:

The ornamental design for a shoelace knot retainer, as shown and described.
